Attorney

UNITED STATES PATENT OFFICE.

MAURICE L. NOVACK, OF MINNEAPOLIS, MINNESOTA.

RING.

Application filed March 13, 1925. Serial No. 15,250.

This invention relates to the art of jewelry and the main object is to provide a highly novel and practical construction of finger ring, the same being of the general type having a so-called "basket mounting" or enlarged crown portion, and which ring is commonly or, at least, frequently worn in connection with and adjacent to a plain band ring. At the present time, such a combination of finger rings is popularly used in engagement and wedding rings, the latter being a band ring while the former quite generally consists of a basket mounting ring supporting a diamond or other precious stone. As the head or crown portion of such engagement or basket mounting rings are usually much broader than the lower or band portion, it is found that a band ring placed next to it will, by reason of the crown, lie at quite a sharp angle to the plane of the larger ring, which not only detracts from the beauty and appearance of the rings, but is also awkward and uncomfortable to the wearer.

To overcome these objections and provide means whereby the rings will accommodate and lie approximately parallel to each other, I have designed and perfected the construction which will now be described and claimed, and which is illustrated in the accompanying drawing, wherein:

Figure 1 is an edge elevation of a ring embodying my invention.

Figure 2 is a view similar to Figure 1, but showing the ring placed upon the finger with a band ring on each side.

Figure 3 is a side elevation of the ring shown in Figure 1.

Figure 4 is a sectional elevation as on the line 4-4 in Figure 3.

Figure 5 is a sectional view as on the line 5-5 in Figure 3.

Figure 6 is a perspective elevation as seen substantially on the line 6-6 in Figure 3.

Figure 7 is a perspective view similar to Figure 6, but showing a modification thereof.

Figure 8 is a side elevation of the ring shown in Figure 7, and a band ring, a portion of the latter being broken out.

Referring to the drawing more particularly and by reference characters, A and B designate rings of the basket mounting type adapted to be worn upon a finger E with one or more band rings, C and D, of common construction. The rings A and B each

consists of a finger receiving band portion 9 which terminates in a crown 10, said crown being (in the present instance) of the basket mounting type, having prongs 11 60 by which the stone (not shown) is set. The prongs are spaced from each other and the crown is substantially hollow, to permit access to all surfaces of the stone for cleaning purposes.

Heretofore, it has been customary to taper or reduce the crown toward the band and to form the inner edge of the crown with the same radius as the band, so that when looking through the ring, a circular opening will be seen, all of which results in the objectionable disadvantages above indicated.

In the present instance, the inner edge of the crown is cut out at 12, as shown, so that its curvature will be approximately 70 the same as the outer circumference of the band ring C or D which is worn next to it, with a result that the two rings may be of the same size and yet be properly worn next to each other, as illustrated. It will thus be 80 seen that the edge of the crown will overlap the band ring, while both rings will remain concentric with each other.

It is not necessary, or in some instances even desirable, to cut away or leave out the 85 entire edge portion of the crown. At the juncture of the crown 10 and band 9, I prefer to leave or form a pair of small ears 13, which are bent inwardly, as shown, so as to give a greater arc to the portion of 90 the ring that abuts the adjacent band ring.

If there is any tendency for the upper end of the band ring to tilt inwardly under the crown, or if there is any necessity for reinforcing the larger ring, the ring may 95 be provided, as shown in Figures 7 and 8, with an auxiliary arc shaped member 14, which is concentric with and complements the band portion 9, by having its ends soldered or otherwise secured between the 100 respective pairs of ears 13. This member 14 is necessarily narrower than the transverse span of the crown so as to leave lateral openings for cleaning purposes, as above mentioned.

It is understood that various modifications may be made in the general design and structural details of the invention as herein illustrated and described, providing, however, that such modifications come within 105 the spirit and scope of the appended claims.

Having now, therefore, fully shown and

described my invention, what I claim to be new and desire to protect by Letters Patent is:

1. A finger ring comprising a band portion and a substantially hollow head portion protruding laterally with respect thereto, one edge of said head portion having an arcuate recess for the reception of a band ring placed parallel with and adjacent to said band portion, and a relatively narrow arc-shaped strip arranged under said head portion and extending longitudinally thereunder, said strip being concentric with and of the same internal diameter as the 15 said band portion.
2. A finger ring comprising a band portion and a substantially hollow head portion protruding laterally with respect thereto, one edge of said head portion having an arcuate recess for the reception of a band ring placed parallel with and adjacent to said band portion and a relatively 20

narrow arc shaped strip arranged under said head portion and extending longitudinally thereunder, the inner surface of said 25 strip forming a circular continuation of the inner surface of said band portion.

3. A finger ring comprising a band portion and a substantially hollow head portion extending therefrom, one edge of said head portion having an arcuate recess for the reception of a band ring placed parallel with and adjacent to said band portion, and a relatively narrow arc shaped strip arranged under said head portion and extending 30 longitudinally thereunder, the inner surface of said strip forming a circular continuation of the inner surface of said band portion, said strip being of the same width as the shank of the ring, as and for the 35 purpose set forth.

In testimony whereof I affix my signature.

MAURICE L. NOVACK
